UNITED STATES PATENT OFFICE.

THOMAS L. KELLY, OF PHILADELPHIA, PENNSYLVANIA.

DESIGN FOR A GAME-BOARD.

SPECIFICATION forming part of Design No. 26,120, dated September 29, 1896.

Application filed August 20, 1896. Serial No. 603,423. Term of patent 3½ years.

To all whom it may concern:

Be it known that I, THOMAS L. KELLY, a citizen of the United States, residing at Philadelphia, in the county of Philadelphia and State of Pennsylvania, have invented and produced a new and original Design for a Game-Board, of which the following is a specification, reference being had to the accompanying drawings, showing part thereof.

Figure 1 represents a plan view of a game-board embodying my design. Fig. 2 represents a section thereof on line *x-x*, Fig. 1. Fig. 3 represents a section thereof on line *y-y*, Fig. 1.

The leading feature of my design for a game-board is a field formed in sections with

recesses in the inner corners thereof and a cross of blocks between the sections.

In the drawings, A designates the field of a game-board, the same consisting of the 20 pieces B B B B, the inner corners of which have recesses C therein. In the center of the space formed by the recesses is the block D, radiating from which are rows E of blocks forming a cross.

What I claim is—

The design for a game-board substantially as described and shown.

THOMAS L. KELLY.
